BOX FOR FRAGILE ARTICLES

William Simon Freeman, Barnsley, England, assignor to William Freeman & Company Limited, Barnsley, England, a British company

Application February 12, 1952, Serial No. 18,494
In Great Britain August 23, 1951

Term of patent 14 years

(Cl. D58—11)

To all whom it may concern:

Be it known that I, William Simon Freeman, a subject of the King of England, residing at Subseal Works, Peel Street, Barnsley, Yorkshire, England, have invented a new, original, and ornamental Design for a Box for Fragile Articles, of which the following is a specification, reference being had to the accompanying drawing, forming part hereof.

Fig. 1 is a top perspective view of the body portion of a box for fragile articles, showing my new design;

Fig. 2 is a bottom perspective view thereof;

Fig. 3 is a cross-sectional view thereof taken on the line A—A of Fig. 1;

Fig. 4 is a cross-sectional view thereof taken on the line B—B of Fig. 2;

Fig. 5 is a top perspective view of an end cap portion of the box;

Fig. 6 is a bottom perspective view thereof;

Fig. 7 is a cross-sectional view thereof taken on the line A—A of Fig. 5; and

Fig. 8 is a front elevational view of the box.

I claim:

The ornamental design for a box for fragile articles, as shown.

WILLIAM SIMON FREEMAN.
